Inventor,
Francis A. Cannon

UNITED STATES PATENT OFFICE.

FRANCIS A. CANNON, OF NEW YORK, N. Y.

IMPROVEMENT IN SAD-IRONS.

Specification forming part of Letters Patent No. 38,728, dated June 2, 1863.

To all whom it may concern:

Be it known that I, FRANCIS A. CANNON, of the city of New York, have invented a new and useful Improvement in Smoothing and Polishing Irons; and I do hereby declare that the following is a full and exact description thereof, reference being had to the accompanying drawings, and to the letters marked thereon.

The nature of my invention consists of a cylindrical metallic roller revolving on its own axis within a slipper made of iron or other metal, a space being left in the bottom of the slipper, at the rear end thereof, sufficiently large to allow the roller to revolve freely, which slipper and the roller are made to fit upon the bottom of a smoothing or sad iron of any of the ordinary forms or shapes. Connected with the handle of the iron is a spring catch to hold the slipper in its desired position.

Figure I is a perspective view of the iron in

the proper position for use, showing the principal parts. Fig. II is a view showing the slipper and roller as attached to the iron. Fig. III is a view of the slipper and roller. Fig. IV is a view of the iron without the slipper and roller.

A represents the slipper; B, the roller; C, the iron. D is the frame of the handle. E is the spring-catch to hold the slipper and roller in position. F is a slot in the frame in which the catch acts.

I claim—

The use of a slipper and roller in combination, made, substantially as described, to fit on the bottom of smoothing-irons, attached thereto and removed therefrom by means of a spring-catch.

FRANCIS A. CANNON.
